HYDRAULIC CONTROL SYSTEM
John H. Province, Bartlesville, Okla., assignor to Phillips
Petroleum Company, a corporation of Delaware
Filed Jan. 3, 1958, Ser. No. 707,024
3 Claims. (Cl. 103—17)

This invention relates to a control system for hydraulic pumps. In one aspect it relates to a hydraulic system to operate pipe tongs, rotary air couplings, derricks, and other equipment. In another aspect it relates to an improved means of control of a prime mover or motor for providing power for operating the above-mentioned equipment.

In oil well servicing operations it is common practice to obtain the power needed to operate the hoist winch, tubing tongs and other units from the truck motor. Modern well servicing units often employ hydraulic pumps for the operation of derricks and other equipment. Thus, a suitable hydraulic pump normally is available on a servicing rig. For this reason I operate a derrick hoist, tubing tongs, and other equipment hydraulically. The hydraulic pump employed to energize the tubing tongs and other equipment is frequently driven by the same truck motor which energizes the hoisting winch. This dual functioning of the motor creates certain difficulties because the motor must be operated at a considerably higher speed when operating the winch than when coupled to the hydraulic pump. In order to prevent the hydraulic pump from being driven at an excessively high speed when the engine is driving the winch, a pneumatically operated clutch system is provided to disengage the drive shaft of the truck from the hydraulic pump when the speed of the motor exceeds a predetermined value. An air coupling is employed in the clutch system.

Accordingly, it is an object of this invention to provide an improved control system for use with a well servicing rig.

Another object is to provide an improved control system to operate tubing tongs and other equipment from the source of hydraulic fluid under pressure.

Another object of this invention is to provide an automatic control system for operating the prime mover or motor which drives a hydraulic pressure fluid pump to increase the motor and pump speed under conditions requiring large volumes of high pressure actuating fluid.

Yet another object of this invention is to provide such an automatic control system which is responsive to hydraulic pressure for increasing hydraulic pressure fluid flow for operating a hydraulic unit requiring a large volume of pressure fluid.

Other objects, advantages and features of this invention will become apparent from the following detailed description which, taken with the attached drawing, forms a part of this specification.

In the drawing FIGURE 1 is a schematic representation of a preferred embodiment of the control system of this invention.

FIGURE 2 is a longitudinal view, partly in section, of a portion of the apparatus of FIGURE 1.

FIGURE 3 is an elevational view, partly in section, of a normally closed pressure switch of FIGURE 1.

FIGURE 4 illustrates in diagrammatic form, a pair of electrical contacts suitable for substitution in the housing illustrated in FIGURE 3 to provide a normally open pressure switch.

FIGURE 5 is an elevational view, partly in section, of a solenoid valve of FIGURE 1.

Specifically, my invention is directed to a control system to regulate the speed of a variable speed driving

2

member comprising in combination, a hydraulic fluid pump driven by said driving member, means for controlling flow of actuating fluid to said driving member, a source of electromotive force, an electrical circuit for 5 communication of electromotive force from said source to said means, a conduit for transmitting pressure fluid, said pump being adapted to pressure said pressure fluid through said conduit, a pressure switch, the switch of said pressure switch being disposed in said electrical circuit, the pressure sensing element of said pressure switch being in operative communication with pressure fluid in said conduit, said pressure sensing element being adapted to close said switch in response to an increase of pressure of said pressure fluid in said conduit above a predetermined pressure thereby actuating said means to increase flow of actuating fluid to said driving member and said pressure sensing element being adapted to open said switch in response to a decrease in pressure of said pressure fluid in said conduit below said predetermined pressure to throttle flow of actuating fluid to said driving member.

Referring now to the drawing and specifically to FIGURE 1, reference numeral 10 identifies a truck motor which is employed to energize a well servicing unit. The speed of a motor is controlled by a butterfly valve in carburetor 11. This valve is positioned by a pneumatically operated controller 13. This controller 13 is actuated by pressure air supplied from the storage tank 14. Tank 14 is connected to an air compressor, not shown, by a line 15. A line 16 extends from tank 14 to the inlet of a throttle valve 17. Air inlet 110 in controller 13 is connected to tank 14 through a line 18 provided with a 3-way solenoid operated valve 23. The outlet of throttle valve 17 is connected to a second air inlet 111 of controller 13 by a line 21. Solenoid valve 23 is controlled by a solenoid 24 which is energized from a voltage source 25. One terminal of voltage source 25 is connected to ground as is one terminal of solenoid 24. The second terminal of voltage source 25 is connected to a second terminal of solenoid 24 by a lead wire 27 provided with a switch 28. Switch 28 is a manually operable switch. A line 22 communicates valve 23 with the atmosphere for venting purposes. In the absence of power, that is, when switch 28 is open, a line 19 communicates through valve 23 and lines 18 and 16 with tank 14. When solenoid 24 is energized, by closing switch 28, line 19 communicates through valve 23 and line 22 to the atmosphere.

The drive shaft of engine 10 is connected through a suitable power take-off 29 and a shaft 30 to one member of a clutch 31. A second member of clutch 31 is connected by a shaft 32 through a coupling or swivel 34 to a hydraulic pump 33. Clutch 31 is engaged by the application of pneumatic pressure thereto through coupling 34. Air pressure for energizing clutch 31 is supplied 50 from a second storage 35 which is connected to line 15 by a line 36 provided with a pressure reducing valve 37. The pressure in tank 35 is less than the pressure in tank 14. Tank 35 is connected to coupling 34 by a line 38 having a solenoid operated 3-way valve 39, conduit 38a, an oiler 40, a conduit 38b, a quick release valve 41 and conduit 38c. Valve 39 is energized by a solenoid 43 which has one terminal connected to the ground. The second terminal is connected to the second terminal of voltage source 25 by a lead 44 which is provided with a manually operated switch 46 and a normally closed pressure operated switch 47. Pressure switch 47 is controlled by the pressure from line 21 through a line 48, pressure above a predetermined value opening the electrical switch 47 and below this value allowing the switch to close.

The quick relief valve 41 is a standard 3-way quick relief valve, more fully illustrated on pages 133 and 134

of the Bendix-Westinghouse Maintenance Manual Number B-W 1116 published in 1952 by the Bendix-Westinghouse Automotive Air-Brake Company. This valve 41 is not necessary to the operation of the system and may be dispensed with, its main purpose being to allow air to vent to the atmosphere through opening 41a (when open) faster than it could vent through line 38b, oiler 40, line 38a, valve 39 and vent line 39a, thereby allowing clutch 31 to release quickly without slipping thereby reducing frictional wear during releasing. Valve 41 consists of a body having a chamber (not shown) with an air supply inlet and preliminary exhaust line 38b, a quick air release outlet opening 41a disposed opposite 38b, and a line 38c connecting one side of the chamber to clutch 31. There is a valve seat around 38b and 41a in the chamber, and a valve head having a flexible annular rim is biased by a spring cord. When pressure in 38b is high, the valve head closes opening 41a and air from 38b passes the flexible rim into line 38c to engage clutch 31. When pressure in clutch 31 balances the high pressure in 38b, the flexible rim closes 38b while the valve head closes 41a. When pressure in 38b falls below that in 38c, the valve head unseats, aided by the spring, opening outlet 41a to clutch line 38c allowing quick release of air to the atmosphere. When high pressure returns to line 38b, the valve head closes opening 41a and pressure air passes the flexible rim into 38c repeating the cycle.

As mentioned, valve 41 is not necessary, and may be eliminated as when either one of electrical switches 46 or 47 is open, solenoid 43 moves valve 39 to connect line 38a to vent line 39a and air is released to the atmosphere through line 38b, oiler 40, line 38a, valve 39 and vent line 39a, while valve 39 is closed to line 38. When both switches 46 and 47 are closed, solenoid 43 actuates valve 39 to close vent line 39a and connect line 38 and 38a, supplying air under pressure from tank 35 to valve 41 and line 38c to clutch 31 to engage said clutch.

The inlet of pump 33 is supplied with hydraulic fluid from an oil storage tank 50 by a line 51 provided with a filter 52. A fluid leakage line 49 returns leakage oil from pump 33 to tank 50. The outlet of pump 33 is connected by a line 53 to a first port 54 of a valve 55. A second port 56 of valve 55 is connected with a first port 57 of a second valve 58 by a line 59. The second port 60 of valve 58 is connected by a line 61 to a first port 62 of a third valve 63. A second port 64 of valve 63 is connected by a line 66 to a fluid opening 69 of a hydraulic motor 67. Motor 67 is connected with a gear box 68 which drives a tubing tongs, not shown. A second fluid opening 70 of motor 67 is connected by a line 71 to a third port 73 in valve 63. A fourth port 74 in valve 63 is connected by a line 76, a check valve 77 and a line 78 through a third port 80 of valve 58. The fourth port 81 of valve 58 is connected by lines 82 and 83 to the oil tank 50. Ports 80 and 74 of respective valves 58 and 63 are connected by line 78, a centering valve 85 and line 76. A third port 87 in valve 55 communicates through a line 88 to supply hydraulic fluid to other apparatus, not shown, which may be employed on the rig. The fluid supplied by line 88 is returned through a line 89 and line 83 to supply tank 50. The fourth port 90 of valve 55 is also connected to return line 83 by a line 91. Line 59, which connects ports 56 and 57 of the respective valve 55 and 58, is connected to tank 50 by a line 92 provided with a pressure relief valve 93. The connection between the ports in valve 55, 58 and 63 are described hereinafter.

The valves 55, 58, 63 and tubing tongs, not shown, are fully described in U.S. Patent 2,780,950 over which this present application is an improvement.

Air coupling or swivel 34 and clutch 31 are also described in detail in Patent 2,780,950. The purpose of coupling 34 is to introduce air from line 38 to FIGURE

1 into a passage in shaft 32. This air pressure in turn actuates clutch 31 to connect shafts 30 and 32.

It might be stated that valves 58 and 63 are very similar to valve 55. The centering valve 85 mentioned above, is also fully described in Patent 2,780,950.

The tubing tongs described in said patent are power tongs which are adapted to be energized by hydraulic motor 67 in accordance with the procedure fully described in said patent.

An electrical circuit 27a is provided for connecting voltage source 25 with solenoid 24. This circuit 27a is provided with a manually operable switch 103 and a pressure actuated switch 102. A pressure sensitive element 101 communicates with pressure in line 92 for actuation of pressure actuated switch 102. Normally, pressure sensitive element 101 and switch 102 are combined in a single unit, such a unit being commercially available.

Details of the pneumatically operated controller 13 are illustrated in FIGURE 2.

This unit comprises a housing unit 112 in which are provided pistons 113 and 117. Piston 113 has a reduced diameter portion indicated at 126. Air pressure in space 114 acts on the adjacent surface of piston 113. The area of piston 113 facing space 114 is relatively large in comparison to the area of a circle having as its diameter the smallest diameter of annular surface 125. A compression spring 115 is installed as illustrated and biases piston 113 in a direction from left to right. Reference numeral 116 identifies the space from which air from inlet 111 presses against piston 117. An O-ring 127 seals space 116 from space 114. Piston 117 is attached to shaft 118 as illustrated. Shaft 118 is not attached to piston 113 but instead is free to move independently of piston 113 except as hereinafter described. The right-hand end of shaft 118 communicates with a compression spring 119, the right-hand end of which is held in position by a nut 128. Nut 128 is provided with a threaded opening 122 for accommodation of a throttle rod 123 (see FIGURE 1) for actuating the butterfly valve of the carburetor 11. Shaft 118 is provided with a shoulder or flange 129 for contacting the enlarged end 124 of sleeve 121. A compression spring 120 is provided as illustrated for biasing sleeve 121 in a direction from right to left of FIGURE 2.

In the operation of the pneumatic operated controller 13 of FIGURE 2, high pressure air introduced into space 114 through air inlet 110 presses against surface 125 of piston 113 and compresses spring 115 to hold the piston 113 against the nut at the left end of housing 112. Under this condition piston 117 will also move to the left under the pressure of spring 119 and spring 120 will force sleeve 121 to the left with the result that the butterfly valve of carburetor 11 will be closed to such an extent that the engine will operate at normal idling speed. If air pressure is removed from space 114, as would happen when valve 23 (FIGURE 1) is actuated to vent space 114, then piston 113 will be urged to the right by spring 115. As piston 113 moves to the right, shaft 118 also moves to the right. When flange 129 contacts enlarged portion 124 of sleeve 121, sleeve 121 and nut 128 will also move to the right. However, sleeve 121 will move to the right only a short distance because the shoulder of piston 113 will contact or approach the right-hand end of space 114 and further movement will be prevented. This small amount of movement of sleeve 121 is sufficient to open the butterfly valve of carburetor 11 a small amount which, in turn, will cause the engine to speed up to a fast idle. Sufficient engine speed is then available to supply fluid to the power tongs by way of motor 67. When it is desired to speed up the engine independently of the fast idle operation just described, high pressure air is admitted to space 116 by way of inlet 111. Pressure of the air against piston 117 initially forces the piston and rod 118 to the right. When flange 129 contacts enlarged end 124 of sleeve 121, additional air pressure is required to move sleeve 121 against the force of spring 120. This

additional air pressure is readily supplied by throttle valve 17 via pipe 21 and the sleeve 121 is moved to the right as far as required up to and including the full open position of butterfly valve 11.

FIGURE 3 illustrates in detail construction of the pressure switch 47 disposed in electrical circuit 44 of FIGURE 1. The working parts of this switch are enclosed within a case 140, this case being divided into two portions by a flexible diaphragm 151. The portion of the case above diaphragm 151 represents a fluid-tight portion while the portion below the diaphragm may or may not be fluid-tight. As used in the apparatus of FIGURE 1 the fluid-tight portion of the pressure switch is provided with a threaded opening 147 for accommodation of pipe or line 48. This switch is illustrated in FIGURE 3 of course as being included within circuit 44. The upper portion or the fluid-tight portion is sealed against leakage to the atmosphere by use of a flexible sealing washer 148 which is held in place by a metal or other rigid washer 149. A rod 141 extends through these several washers and serves as a connection to which one lead of circuit 44 is attached. This rod extends into the casing and terminates as one contact point of a pair of contact points 146. These contact points are normally closed contact points. The lower portion of the switch includes rod 145, to the lower portion of which is connected the other terminal of circuit 44. This circuit is completed between the lower of the two contact points 146 and rod 145 by a member 142, and metal washers 152 and 144, and spring 143. Washer 144 rests upon a flexible washer 150.

FIGURE 4 is intended to represent a pressure operative switch in general similar to switch illustrated in FIGURE 3 with the exception that it is a normally open switch. Like reference numerals in FIGURES 3 and 4 identify similar pieces of apparatus. Rods 141 and 145, contacts 146a, member 142, spring 143 and washer 144 of FIGURE 4 complete the circuit 27a. The normally open contact points are illustrated in FIGURE 4 and are identified by reference numeral 146a. A housing suitable for enclosing the apparatus parts of FIGURE 4 is, if desired, similar to that illustrated in FIGURE 3 and accordingly it will not be described in detail. Flexible diaphragm 151 in FIGURE 4 also separates the portion thereabove as a fluid-tight portion of the pressure switch.

In FIGURE 5 is illustrated, diagrammatically and in detail, the solenoid 3-way valve 23 of FIGURE 1. The solenoid 24 is illustrated as having one terminal connected to circuit 27 and the other terminal grounded. The valve portion of this solenoid valve is illustrated as having a common outlet on one side attached to line 19 and an outlet connected to vent line 22 disposed in such a manner that upon flow of electrical current through the solenoid the valve is lowered and opened to the flow of pressure air from line 19 through the vent line 22. Upon opening circuit 27 the valve raises under the influence of a compression spring 161 to admit pressure air from line 18 through line 19 to the pressure operated controller 13.

In the operation of this hydraulic system and in reference to FIGURE 1 the manually operable switch 46 is closed to energize solenoid 43. With solenoid 43 energized valve 39 opens to admit air pressure from pipe 38 and tank 35 to rotary coupling or air swivel member 34 and shaft 32 to clutch 31. The application of air pressure to clutch 31 results in shaft 32 being coupled with shaft 30 to drive pump 33. The pneumatically operated controller 13 is set so that with switch 46 closed and switch 28 open, the motor 10 operates at normal idle speed and drives pump 33 at a speed sufficient to supply power fluid for the operation of those hydraulic units which require a comparatively small amount of fluid, such as a derrick raising mechanism, sucker rod tongs, etc.

When switch 28 is closed to complete a circuit through solenoid 24, valve 23 is actuated to vent pressure from

line 19 through 22. When solenoid 24 is energized, the valve portion of the valve 23 moves downward against compression of spring 161. The venting of air pressure from line 19 results in opening the butterfly valve of the carburetor with the motor 10 operating at a fast idle speed thereby driving pump 33 at a faster speed sufficient to supply power fluid at a desired rate to drive those hydraulic units requiring a larger amount of fluid, such as tubing tongs.

10 Rotation of shaft 32 drives pump 33 so that hydraulic fluid is withdrawn from tank 50 through line 51 and delivered to line 53 under pressure. A return line 49 is provided between pump 33 and tank 50 for return of fluid which may leak from pump 33. When it is desired to operate any of the auxiliary equipment, not shown, valve 55 is adjusted so that ports 54 and 87 are in communication as are ports 56 and 90. The fluid under pressure is then transmitted to the auxiliary equipment 15 through a line 88 and is returned therefrom to tank 50 through lines 89 and 83.

In order to energize power tongs in a forward direction, valve 55 is set such that ports 54 and 56 are in communication as are ports 87 and 90. Valve 58 is set so that ports 57 and 60 are in communication as are ports 80 and 81. Valve 63 is set so that ports 62 and 64 are in communication as are ports 73 and 74. Under these conditions, the fluid from pump 33 passes through line 53, valve 55, line 59, valve 58, line 61, valve 63 and line 66 to the opening 69 of motor 67. Fluid is returned to tank 50 from motor 67 through opening 70, line 71, valve 63, line 76, check valve 77, line 78, valve 58, line 82 and line 83. When each pipe joint has been tightened it is 20 then necessary to remove the tongs from the pipe.

When the power tongs are employed to unscrew pipe

sections valve 58 is positioned such that ports 57 and 60 are in communication as are ports 80 and 81. Valve 63 is positioned so that ports 62 and 73 are in communication as are ports 64 and 74. The fluid under pressure is then transmitted from line 59 through valve 58, line 61, valve 63, and line 71 to port 70 of motor 67. Fluid is returned to tank 50 through line 66, valve 63, line 76, check valve 77, line 78, valve 58, lines 82 and line 83.

45 In order to center the tubing tongs when operated in the reverse direction, valve 58 is reversed. Fluid is then transmitted from line 59 to valves 58, line 78, centering stop valve 85, line 76, valve 63 and line 66 to port 69 of motor 67. The return fluid is transmitted to tank 50 through line 71, valve 63, line 61, valve 58, lines 82 and 83.

50 A second power take-off 12 is provided near the drive shaft end of engine 10. This power take-off provides power for pulling casing and for such other uses as require high engine speeds with a mechanical direct drive takeoff, that is, a non-hydraulic drive.

The handle of the reversing valve 63 has a neutral position intermediate its line of movement. When this 60 valve handle is in its right hand position pipes 61 and 66 are connected and pipes 71 and 76 are connected to permit flow of hydraulic fluid through motor 67 in one direction. When this valve handle is moved to the left of the center neutral, the motor 67 is reversed by closing 65 off flow of fluid through the pipes just mentioned and connecting pipes 61 to 71 and pipes 66 to 76. In the valve handle neutral or center position pipe 61 is connected to pipe 76 to by-pass completely the motor 67.

70 This by-pass involves passage of hydraulic fluid from pump 33 through pipe 53, valve 55, pipe 59, valve 58, pipe 61, valve 63, pipe 76, check valve 77, pipe 78, valve 58, pipe 82 and pipe 83 to storage 50. In this manner the hydraulic liquid is performing no useful work and the 75 pressure from pump to storage is merely that caused by

flow through the just mentioned pipes and valves. However, when valve 63 is actuated to operate motor 67, the pressure drop from pump to storage is markedly increased due to the load on motor 67 for operating power tongs, for example. With switch 28 and circuit 27 open and switch 103 in circuit 27a closed, this increase in pressure drop from pump to storage is evidenced in line 92 by an increase in pressure therein. This increase in pressure is sensed by the pressure sensing apparatus 101, and switch 102 is closed thereby, thus venting pressure air from line 19 through the solenoid valve 23 and vent line 22. Upon venting pressure air from line 19, the pneumatic operated controller 13 actuates to allow movement to a piston assembly 112a to the right which movement increases somewhat the flow of fuel to the engine. Sufficient engine speed is then available to supply fluid to the power tongs by way of motor 67. If it is desired to pull tubing, throttle valve 17 is opened to admit pressure air to line 21 and thence through inlet 111 to piston 117 of pneumatic controller 13 to increase engine speed. Upon opening throttle valve 17 pressure air flows from pipe 21 through pipe 48 to actuate pressure switch 47 to disengage clutch 31 so that pump 33 will be inoperative. It is immaterial whether switch 103 is opened or closed when switch 28 is closed because the latter overrides action of the pressure assembly 101-102 in maintaining valve 23 in its venting position.

By providing circuit 27a with a pressure switch assembly 101-102, the motor is automatically speeded up an amount sufficient to supply just enough hydraulic fluid from pump 33 to operate power tongs or other hydraulically operable equipment without overspeeding pump 33. By the use of this invention I am able to use hydraulic pump 33 as long as 24 to 30 months between overhaul periods in contrast to need for pump overhauling each 3 to 6 months when my invention is not used.

While certain embodiments of the invention have been described for illustrative purposes, the invention obviously is not limited thereto.

I claim:

1. A control system for regulating the speed of a variable speed driving member comprising, in combination, a variable speed driving member having an actuating fluid flow control valve in operative communication with said driving member, a hydraulic fluid pump driven by said driving member, a pneumatically operable spring biased controller operatively connected with said actuating fluid flow control valve, a source of pneumatic fluid under a superatmospheric pressure, a first conduit communicating said source of pneumatic fluid under pressure with said controller, a 3-way solenoid valve in said conduit, a source of electromotive force, an electrical circuit communicating said source of electromotive force with the solenoid of said valve, a second conduit leading from said pump for transmission of hydraulic fluid under pressure, a pressure switch, the switch of said pressure switch being disposed in said circuit, the pressure sensing element of said pressure switch being in operative communication with said hydraulic fluid in said second conduit, said pressure sensing element being adapted to close said switch in response to a predetermined pressure of said hydraulic fluid in said second conduit above a pressure produced by a low idling speed of said driving member thereby causing said 3-way valve to vent pneumatic fluid from said controller whereby said spring biases open said actuating fluid flow control valve to increase the speed of said driving member to a fast idling speed, and said pressure sensing element being adapted to open said switch in response to a pressure below said predetermined pressure of said hydraulic fluid in said second conduit thereby causing said 3-way valve to open said first conduit to

said controller thereby admitting pneumatic fluid under pressure to said controller thereby actuating said spring loaded controller against its bias and throttling said actuating fluid flow control valve to decrease the speed of said driving member to a normal idling speed thereby providing said hydraulic fluid under sufficient pressure only for light duty service.

2. A control system to regulate speed of a variable speed driving member comprising, in combination, a variable speed driving member, a hydraulic fluid pump driven by said driving member, a source of pneumatic fluid, a spring loaded pneumatic controller, a first conduit communicating said source of pneumatic fluid under pressure with said controller, said pneumatic controller being operatively connected with said driving member for regulating flow of fuel thereto, an electrically operative 3-way motor valve in said first conduit, a source of electromotive force, an electrical circuit communicating said source of electromotive force with the motor of said motor valve, a second conduit operably communicating said pump with a point of hydraulic fluid use, a hydraulic fluid, in said pump and said second conduit, a pressure switch having a pressure sensing element operatively connected therewith, the switch of said pressure switch being disposed in said electrical circuit and said pressure sensing element being in operative communication with said second conduit, said 3-way valve having a vent, said pressure sensing element upon sensing a pressure higher than a predetermined pressure closing the switch of the pressure switch to complete said electrical circuit to the motor of said motor valve thereby communicating said first conduit intermediate said pneumatic controller and said 3-way valve with said vent whereby the spring of said controller biases said controller in such a manner as to increase the speed of said driving member to a fast idling speed and provides high pressure hydraulic fluid for heavy duty service, and said pressure sensing element upon sensing a pressure below said predetermined pressure opens said switch thereby opening said electrical circuit and thereby communicating said first conduit intermediate said pneumatic controller and said 3-way valve with the first conduit intermediate said 3-way valve and said source of pneumatic fluid whereby said pneumatic fluid biases said spring of said controller in such a manner as to decrease the speed of said driving member to a normal idling speed thereby providing hydraulic fluid below said predetermined pressure for normal light duty service.

3. An internal combustion engine throttling control assembly comprising, in combination, a variable speed internal combustion engine, a throttle valve in operative communication with said engine, a pneumatically operable spring loaded controller, said controller being operatively connected with said throttle valve, a source of pneumatic fluid under pressure, a first conduit communicating said controller with said source of pneumatic fluid under pressure, an electrically operative 3-way motor valve in said conduit, a source of electromotive force, an electrical circuit communicating said source of electromotive force with the motor of said valve, a pressure switch having a pressure sensing element operatively connected with the switch, a hydraulic pump operatively connected with said engine, a hydraulic pressure restricting means, a second conduit communicating said pump with said pressure restricting means, hydraulic fluid in said pump and in said second conduit, said switch being disposed in said circuit, said pressure sensing element operatively communicating with said second conduit and being adapted to close said switch on sensing a pressure above a predetermined pressure thereby actuating said motor valve to vent pneumatic fluid under pressure from said controller and actuating said spring loaded controller

to open said throttle valve thereby providing fuel to said motor for fast idling speed, and said pressure sensing element being adapted to open said switch upon sensing a pressure below said predetermined pressure thereby actuating said motor valve to admit pneumatic fluid under pressure to said controller and actuating said controller against its bias to close said throttle valve thereby providing fuel to said motor for normal idling speed.
